VANE PUMP

Jesse S. Wentworth, Cincinnati, Ohio, assignor to
 Wentworth and Hull, a mutual co-partnership
 composed of Jesse S. Wentworth and Bertram
 G. Hull, Cincinnati, Ohio

Application May 25, 1939, Serial No. 275,643

8 Claims. (CL 230—139)

This invention relates to improvements in pumps, such as are used in connection with mechanical or electrical refrigerators, for delivering fluid or gas under pressure, and for similar purposes.

One of the principal objects of this invention is the provision of such a pump, which is compact in size and relatively inexpensive to manufacture, yet highly efficient in operation.

Another object of this invention is the provision of a pump in which the friction between moving parts is reduced to a minimum, thereby reducing wear between the parts and materially extending the life of such pumps.

A further object of this invention is the provision of a pump as above described, which is substantially without packing, and in which the parts are so related to one another as to prevent leakage and losses, despite no packing around the pump shaft.

A still further object of this invention is the provision of a pump to be used as a compressor in connection with mechanical and electrical refrigerators, and in which solid particles and globules of oil are removed from the gas before the compressed gas is injected into the compressed gas line.

A still further object of this invention is to arrange the pump and its driving means with respect to one another, whereby only the height of one of these members is required to take in both the pump and its driving means.

A still further and specific object of this invention is the provision of a pump as above referred to, in which the friction is reduced to a minimum, in that only an oscillatory, sliding contact between the rotor and its housing is had, instead of a constantly running engagement.

It is also an object of this invention to provide an adjusting means for adjusting the throw of the eccentric to take care of possible small errors in manufacture, and also to take up possible wear between the parts.

A still further object of this invention is the provision of a pump of the class above referred to, wherein the eccentric throw of the pump rotor may be varied or adjusted to increase and decrease pressure thereof on the housing, and wherein this decrease is employed to reduce the starting torque necessary in initially starting the pump.

It is also an object of this invention to provide a pump wherein the pressure between the pump rotor and its housing is reduced to zero before the

pump is started, and the pressure then raised to a maximum after the pump is running.

Other objects and advantages of the present invention should be readily apparent by reference to the following specification, considered in conjunction with the accompanying drawings forming a part thereof, and it is to be understood that any modifications may be made in the exact structural details there shown and described, 10. within the scope of the appended claims and without departing from or exceeding the spirit of the invention.

In the drawings:

Fig. 1 is a vertical, sectional view through a 15. combined pump and motor, assembled in its preferred form.

Fig. 2 is an elevational view of the pump of Fig. 1, as seen from the bottom thereof.

Fig. 3 is a horizontal, sectional view, taken on 20 line 3—3 of Fig. 1.

Fig. 4 is a horizontal, sectional view, taken on line 4—4 of Fig. 1.

Fig. 5 is a fragmentary, horizontal, sectional view, taken in a plane below Fig. 4, and showing the parts in a second position of adjustment.

Fig. 6 is a fragmentary, sectional view, showing parts in elevation, and taken on line 6—6 of Fig. 1.

Fig. 7 is an enlarged, horizontal, sectional view, taken on line 7—7 of Fig. 1.

Fig. 8 is a vertical, sectional view through the lower end of Fig. 1, and taken on line 8—8 of Fig. 7.

Fig. 9 is a perspective view of the pump wing utilized in this application, said wing being illustrated on an enlarged scale over that shown in the other views.

Fig. 10 is a vertical, sectional view through a 40. pump and its drive motor, illustrating a modification therein.

Fig. 11 is a transverse, sectional view, taken on line 11—11 of Fig. 10.

Fig. 12 is a fragmentary, horizontal, sectional view, taken on line 12—12 of Fig. 10.

Fig. 13 is a fragmentary, sectional view, taken on line 13—13 of Fig. 10.

Fig. 14 is a fragmentary, vertical sectional view, taken on line 14—14 of Fig. 13.

Fig. 15 is a vertical, sectional view, similar to Figs. 1 and 10, through a pump and its drive motor, illustrating further modifications in the construction and operation thereof.

Fig. 16 is a horizontal, sectional view, taken 55. on line 16—16 of Fig. 15.

Fig. 17 is a fragmentary, horizontal, sectional view, taken on line 17—17 of Fig. 15.

Fig. 18 is a view, similar to Fig. 16, taken in a plane below that of Fig. 16, on line 18—18 of Fig. 15.

Fig. 19 is a vertical, sectional view, on an enlarged scale, of the pump mechanism of Fig. 10, and showing certain modifications therein whereby the throw of the pump impeller may be adjusted.

Fig. 20 is a transverse, sectional view of a portion of the disclosure in Fig. 19, taken on line 20—20 of Fig. 19.

Fig. 21 is a view similar to that shown in Fig. 20, with the parts in an adjusted position to one side of that shown in Fig. 21.

Fig. 22 is a view similar to that shown in Fig. 21, with the parts in the opposite position of adjustment.

Fig. 23 is a bottom plan view of the pump mechanism of Fig. 19, taken on line 23—23 of Fig. 19, showing the means for obtaining the adjustments of Figs. 20, 21 and 22.

Fig. 24 is a view very similar to that of Fig. 23, showing the means for automatically effecting the adjustments of Figs. 20, 21 and 22.

Fig. 25 is a wiring diagram showing the connection of the motor fields and solenoid employed in effecting the automatic adjustment of the parts.

Throughout the several views of the drawings, similar reference characters are employed to denote the same or similar parts.

As was noted above, this invention pertains to a pump for use in connection with mechanical or electrical refrigerators, and similar purposes, where it is desired to compress gases or fluids or to transfer liquids or fluids under pressure. It is also one of the chief purposes of this invention to supply such a pump or compressor unit in which the parts are intimately associated with one another and enclosed in substantially a single housing, whereby the manufacturing costs may be materially reduced and required accommodating space likewise reduced to a minimum.

Specifically referring to the drawings, and particularly to Figs. 1 to 9 inclusive, which illustrates the preferred embodiment of this invention, it will be noted that use is made of an upper housing 25 and a lower housing 26. These housings are substantially cup shaped and have, respectively at their adjacent ends, radial flanges 27 and 28, through which pass locking or clamp screws or bolts 29. If desired, a gasket (not shown) may be inserted between said flanges for making the interior of the housings air and gas tight to the exterior. In addition, each of the housings 25 and 26 have projecting from their outer surfaces, fins 30 and 31 for radiating heat generated and developed within the housings.

The upper housing 25 is counter bored to provide a shoulder or seat 32, against which the motor field laminations 33 abut, and the seat 32 forms a shoulder which, along with the inner overhanging portion 34 of radial flange 28, affords means for clamping the motor field laminations in position. Associated with said laminations, as is usual practice, is the motor field coil 35. Secured to the upper housing 25, and passing through the wall thereof, is a sealed-in plug or connector 36, through which the external electric source or wires 93 is connected with the motor field coil 35.

Centrally of the motor field laminations 33 are the armature laminations shown here as secured

over the pump assembly, and indicated in general by the reference numeral 37. In other words, the motor armature has built within its center the pump or compressor, whereby the rotation of the motor armature operates the pump.

The pump assembly 38 comprises a central pump cylinder 39 in the form of a ring or sleeve, having secured to its upper end a plate 40, and to its lower end a second plate 41. The plates 10 40 and 41 respectively have projecting outwardly thereof bearings or trunnions 42 and 43, respectively received in inwardly projecting bearing bosses 44 and 45, formed integral with the housings 25 and 26, and projecting toward one another. The plates 40 and 41, and their respective sleeves 42 and 43, are each provided with a bore in axial alignment, and which bores are concentric with the inner housing sleeve 39 when in assembled position. The securing of end 20 plates 40 and 41 to sleeve 39 provides, interiorly of said sleeve, a chamber 46 in which is disposed the pump rotor 47, which is in the form of a sleeve, centrally bored and having an external diameter less than the internal diameter of the cylinder sleeve 39.

Disposed in the bores of closure plate sleeves 42 and 43 are the ends of a shaft 48, which has its central portion enlarged and eccentric to the ends, as at 49, and with this eccentric portion disposed 30 within the bore of the rotor 47. The eccentricity of the central portion 49 to its bearing ends is such that the rotor 47 has at all times tangential line contact with the inner surface of the cylinder ring 39 or chamber 46, as seen clearly in Figs. 4 and 5. It will be noted that there is no positive connection between the shaft 48 and rotor 47, since, in fact, and as will later appear, the shaft 48 is always held stationary, and the rotor is loose thereon.

40 In order to hold the shaft 48 stationary, the upper end thereof, see Fig. 6, is formed to provide a pair of flats 50 which are received in an aperture, having the cross section of the end of the shaft, and formed in a lever or wrench 51. 45 This wrench, see Fig. 1, is located within a cavity 52, formed within the bearing boss 44 and in the main lies above the upper surface of closure plate sleeve 42. Referring again to Fig. 6, the wrench or lever 51 has, at its other end, an aperture 53, through which passes a clamp screw 55, threaded into the base of the cavity 52 and therefore into the stationary bearing lug 44. From the description just given, it will be noted 50 that the wrench or lever 51 holds the shaft 48 against rotation. It will also be noted that the pump cylinder 39, and end closure plates 40 and 41 are rotated around the shaft 48, particularly 55 around the eccentric portion 49 thereof, as is also the rotor member 47.

60 In order to rotate the rotor member 47, it is connected with the pump cylinder 39 by a pump wing or vane 58, shown most clearly in Fig. 9, and shown in two operative positions in Figs. 4 and 5. As will be seen, the wing 58 has a hinge 65 connection with both the cylinder member 39 and the rotor member 47, and for this reason the wing or vane 58 is provided at opposite ends with hinge portions or knuckles 59 and 60, respectively connected with one another by a web 61.

70 The hinge or knuckle 59 is disposed in a bearing 62 formed vertically of the pump member 47, while the hinge or knuckle 60 is likewise received in a bearing 63 formed in the cylinder 39. With the wing having its hinge or knuckle portions in their respective bearings, the web 61

crosses the chamber 46, dividing same into a pair of chambers 46' and 46'', respectively being intake or suction chamber and exhaust or pressure chamber, depending upon the direction of rotation of the parts. With the parts in the position illustrated in the drawings, and rotated in the direction of arrow 64 on Fig. 4, the chamber 46' is the discharge or compression chamber and 46'' is the intake or suction chamber.

Extending through the rotor from the discharge or compression chamber 46' is a port 65, communicated with a groove 66 formed circumferentially and exteriorly in the eccentric portion of the shaft at a point near the upper end thereof. Extending from the groove 66 into the shaft is a port 67 which communicates with a vertical port or bore 68 in said shaft, which has its lower end closed and upper end communicating with the cavity 52. Likewise, the intake or suction chamber 46'' has extending from it, through the pump member, a port 69 which communicates with a groove 70 formed circumferentially and exteriorly of the eccentric portion of the shaft at a point near the lower end thereof. This groove 70 communicates through a port 71 with a vertical port or bore 72 in the lower end of the shaft, and which bore or port 72 has its upper end closed and its lower end communicating with a cavity 73, located below the shaft 48 and within the closure plate sleeve 43. It will be noted that this pump shaft is, to all intents and purposes, identical with the plugged shaft disclosed in J. S. Wentworth's United States Patent No. 2,135,881, issued November 8, 1938.

The cavity 73 is connected with a suction or supply port 74 formed along the bottom of the housing 26, and which supply port is connected with the usual fluid or liquid supply tank (not shown). Between the supply port 74 and cavity 73 is a one-way check valve, which may be of any suitable or desirable construction. As shown in the drawings, the check valve 75 is conical shaped, having extending therefrom a stem 76 disposed for guiding purposes in a spider 77 located within the cavity 73 and below the shaft 48. Between the valve 75, and surrounding the valve stem 76, and the spider 77 is a spring 78, which abuts on one end with the spider 77 and on the other end with the valve 75 for at all times urging the check valve to a closed position.

Between the cavity 52 and the vertical discharge or compression port 68 is a check valve 79, similar in all respects to the check valve 75, and likewise spring loaded. The stem of check valve 79 is mounted, for guiding purposes, in a bore centrally of a plate 80 which defines the upper end of the cavity 52, and which plate 80 has on its other side a second cavity 81 formed between itself and a closure plate 82. Within the cavity 81, and located at the perimeter of the plate 80 is a ring 83, having formed therethrough radial bores 84, whereby communication between the cavity 81 may be had through bores or ports 85 formed angularly through the bearing boss 44, with the interior of the housings 25 and 26. The interior of the housings is likewise in communication with the cavity 52, through vertical and radial bores or ports 86 formed in the bearing boss 44.

On the upper surface of the motor rotor laminations 37 are a pair of baffles 87 and 88, respectively circular and disposed at diametrically opposite points of vertical bores or apertures 89 formed through the rotor laminations. The baffle 88 is provided at its upper end with a ra-

dial flange 90, stopping short of the bearing boss 44 to provide a passage way 91.

It should be noted that the interior of the housing 25, above the motor laminations, forms a pressure chamber, while the space below the said laminations forms a lubricating oil chamber with these chambers in substantial unrestricted communication by way of the bores 89 and the necessary clearance between the rotor laminations and field laminations. It should also be noted that oil for lubricating the bearing surfaces of the running parts is fed into the supply port and carried to these surfaces by the gases and fluids being circulated. For this purpose, use is made of a small pipe 92, connecting the oil chamber, or lower end of the housing, with the supply port 74.

The operation of the pump is as follows:

The electric power is supplied through the lead wires 93, through the plug 36, to the motor field coil for energizing same and causing the rotation of the motor armature 37. Since this armature has secured thereto the pump mechanism, the pump is rotated therewith about the shaft 48. The shaft 48, being stationary, causes the pump mechanism to revolve around its eccentric portion 49. The rotation of the pump mechanism around the eccentric portion 49 of the shaft, causes the pump rotor 47 to roll its outer periphery on the inner periphery of the pump cylinder 39 in much the same manner that a small planetary gear would roll within an internal gear. Since, however, the pump rotor and cylinder ring are connected with one another by the wing or vane 58 against independent rotation, these members rotate as a unit, with a slight slippage therebetween.

As will readily be appreciated, this slight relative movement causes the wing or vane 58 to move from the position illustrated in Fig. 5 to the position illustrated in Fig. 4, and then back again to the position of Fig. 5 during each rotation of the pump mechanism, and therefore of the motor rotor. This causes an increase in the suction chamber 46'' and a corresponding reduction of the discharge or compression chamber 46', thereby creating a suction or vacuum in the chamber 46'', which unseats check valve 75, drawing gas or fluid through the port 74 and subsequently compressing this gas or fluid and ejecting same from the chamber 46', thereby unseating the check valve 79 and filling the cavity 52.

The compressed gases and fluids in the cavity 52 pass down through vertical and radial ports 86, and are discharged against the baffle 87. This baffle 87 causes the gas or fluid to slide thereover and have the oil suspended therein removed whereupon the gas or fluid engages the baffle 88-90. In striking the baffles 87 and 88-90, practically all of the oil supplied to the gas and fluid by way of pipe 92 is centrifugally removed therefrom, thereby completely removing any suspended oil or moisture from the gas or fluid, and providing substantially oil free compressed gas which flows from the baffles through the passage way 91.

This oil or fluid collects on the inner surfaces of the baffle 88-90 and flows downwardly through the bores or apertures 89 in the motor armature, allowing the gas and fluid to pass outwardly through baffle outlet 91 into the pressure chamber, where it flows through the angular ports 85 and ring ports 84 into the cavity 81. The gas and fluid escapes from the cavity 81

through final discharge port 94 and the pipe or conduit normally connected therewith.

It will be appreciated that the oil separated from the gas, as noted above, is collected in the interior of the lower housing 26 and rises to a point just below the field and motor laminations. When the motor is shut off, as when the refrigerating system reaches the desired gas compression point, a vacuum is left in the gas or fluid supply tank and in the pipe or conduit connected with the supply port 74, and this vacuum is likewise in the said port 74. With the motor and pump quiescent, this vacuum will tend to suck the oil from within the housing 26 into the gas or fluid supply tank, and gravity flow of the oil to the lowest point may drain all the oil into the supply tank. In order to prevent this, a check valve is placed in the port 74 at the most convenient or desirable point, which is shown in the drawings as at the end of this port. This check valve, indicated in general by the reference character 129, may take any desirable or acceptable form, and that shown in the drawings comprises a nipple 95, threaded into the end of the port 74, which has a passage therethrough and at the same time forms a seat for one end of a spring 96 which bears on its other end against a ball valve 97. The ball valve 97 is held to a seat at the inner end of a port 98, formed through a coupling 99, which is in turn threaded onto the nipple 95.

It will be readily appreciated that the cessation of suction in the suction chamber 46' will allow both the check valve 75 and ball check 97 to seat, thereby stopping any return flow in the suction system of the line, and any lubricant or oil that is in the housing 26 will flow by gravity into the port 74 between these check valves and will not be drawn into the supply tank.

With this construction, also, when the motor is again started, and thereby the pump, the first flow through the system is lubricating oil, which floods all of the rotating parts, and by supplying bearings or their bushings with suitable oil feeding grooves, the lubricating oil is distributed throughout the running bearing surfaces, and since the oil is almost immediately supplied to these bearings upon the starting up of the motor and the pump, the bearings are without lubricant at substantially no time during their rotation.

As is usual practice, and in order to hold the temperature of the pump or motor to a minimum at all times, both the upper and lower housings 25 and 26, as above indicated, are respectfully provided with radiating fins 30 and 31 substantially throughout their exterior surfaces.

In the mechanism just described, the pump and its prime mover are built one within the other, while in the modified construction disclosed in Figs. 10 to 14 inclusive, the pump and motor structures are built independently of one another, and subsequently secured to one another, but including the same principles of construction and operation. Specifically referring to the construction disclosed in Figs. 10 to 14 inclusive, use is there made of a housing 25', in which is mounted the motor field laminations 33 shown as disposed between the shoulder 32 within the housing 25' and the upper end of a pair of pins 102 which upstand from a plate 103 partly disposed within the housing 25'. The motor rotor laminations 37, instead of being se-

cured to the pump cylinder, are secured in the usual manner to a motor shaft 104 which has its upper end journaled in a bearing boss 105. The lower end of the shaft 104 is journaled in a bearing boss 106 integral with the plate 103, and this bearing being shown in the drawings as including a bearing bushing 107 carried by the boss 106 and receiving the lower end 108 of the shaft 104.

10 An outer pump housing casting 26' is utilized and has at its upper end the radial flange 28 which engages a radial flange 27 at the lower end of the motor housing 25', and these flanges are secured to one another by the connecting screws or bolts 29, and between them the usual gasket for sealing this joint. The said connecting screws or bolts provide the clamping pressure for holding the field laminations 33 in compressed superimposed position between the upper ends of the pins 102 and the housing shoulder 32, since the plate 103 is secured as by clamp bolts 109 to the casting 26'.

15 Secured to the undersurface of the plate 103, as by bolts or screws 110, is a sleeve 111 carrying at its other end a bearing plate 112. Within the sleeve 111 is the pump cylinder sleeve 39 which carries at its opposite ends closure plates 40 and 41, from which respectively project the trunnions or bearing sleeves 42' and 43'. The sleeve 42', in addition to forming interiorly thereof the bearing for the pump shaft 48, forms 20 additionally a clutch or connection with the motor drive shaft 104. This clutch is clearly shown in Fig. 12 and has several clutch teeth 113 projecting therefrom intermeshing with similar complementary clutch teeth 114 formed on the upper ends of the pins 102.

25 Within the pump cylinder 39 is the pump rotor 47, connected with the pump cylinder by the double hinge wing or vane 58, and which operates in the same manner as that above described, and is rotated through the drive of the pump cylinder about the eccentric portion 49 of the shaft 48. The internal construction of the shaft 49, in Fig. 10, is substantially identical with that disclosed in Fig. 1, except that the ends of the shaft are provided with counter bores in order that the intake and exhaust valves respectively 75 and 76 may be positioned much nearer to the intake and supply ports respectively 69 and 65, so as to reduce any possible re-expansion in the gas during the cycle of the pump. The discharge port 68 in the pump shaft 48 connects 30 with a bore 115 formed through the center of the plate trunnion and bearing sleeve 42', and motor shaft 104 connected with a cavity 116 formed within the housing bearing lug 105. This cavity 116 has its upper end defined by an imperforate plate 117 held to its seat within the cavity by a cap 118 and lugs 119 projecting therefrom. The cavity 116 communicates with the interior of the housing 25' by way of ports 120 with the baffles 87 and 88-90 in the path of flow therethrough. The interior of the housing 25' communicates by way of angular ports 121 with a chamber or cavity 122 formed between the above mentioned imperforate plate 117 and closure cap 118, and this cavity 122 communicates with the discharge or pressure port 94 and a pipe or conduit (not shown) connected therewith.

35 The interior of the housing 26' communicates with the interior of the housing 25' by way of vertical ports 123 formed through the plate 103,

and which ports deliver the separated lubricating oil into the housing 26' for injection into the system in the same manner as above described.

The shaft 48, in Fig. 10, similar to said shaft in Fig. 1, is held stationary by a lever or wrench 124 connected therewith in the same manner as the lever or wrench key 51 and locked in position by a screw or bolt 125 passing into the bearing plate 112. The lower bored end of the shaft 48 projects beyond the lever or wrench 124 into a coupling 126 which has connected therewith one end of a tube 127 lying below the bearing plate 112, and which tube takes the place of the supply port 74, and is connected with the supply tank (not shown). A small bleed hole 128 is formed through one wall of the tube to provide for the injection of the oil into the system. The tube 127 is projected, at a suitable point, through the wall of the housing 26' and has connected therewith the oil check valve 129, which may be of any suitable or desirable construction, such as above described.

In order to prevent the shifting of the motor field laminations 33, a construction similar to that illustrated in Figs. 13 and 14 may be employed, wherein a pin 132 is arranged half within the inner wall of the housing 25' and half within the field laminations 33. In order that this pin 132 may be removed, in the event it is desired to take out the field laminations, it is provided with a finger hold or shoulder 133.

The operation of the combined motor and pump structure in Figs. 10 to 14 inclusive is substantially identical with that above described in connection with the structure in Figs. 1 to 9 inclusive. In other words, rotation of motor armature 37 carries with it the motor shaft 104, which, through its clutch connection 113-114 with the pump cylinder 39, rotates this housing. The rotation of the pump housing 39, through the double hinge vane 58, rotates the pump rotor, thereby effecting a pumping and compressing action through the pump.

The path of flow is from the supply tank (not shown), oil check valve mechanism 129, pipe or conduit 127, port in the lower end of the shaft 48, check valve 75, radial ports 69 into the chamber 46''. The pressure flow is from this chamber, when converted into the compression chamber 46', through the radial port 65, vertical port 68 in the upper end of shaft 48, past the check valve 76, port 115 in the closure plate trunnion and bearing sleeve 42' and motor shaft 104, cavity 116, vertical ports 120, interior of housing 25', angular ports 121, cavity 122 and exhaust port 94 and conduit and storage tank (not shown) connected with the port 94. The flow of fluid from the supply tank to the pump supply chamber 46'' carries with it lubricating oil drawn through bleed hole 128 in the pipe or conduit 127. The flow of the compressed gas or fluid from cavity 116 to the cavity 117 is by way of baffles 87 and 88-90 for removing the lubricating oil therein as above described, and for directing the lubricating oil through the vertical bores 89 in the motor rotor 37. This separated lubricating oil flows by way of ports 123 to the interior of the housing 26' and is collected therein, as well as in the inverted cup shaped lower housing closure plate 130 secured to the open end of the lower housing by means of bolts or screws 131.

In connection with the construction just described and illustrated in Figs. 10 to 14 inclusive, it should be noted that the use of the clutch 113-114 between the motor shaft 104 and driven

pump member 39 is advantageous in compensating for slight inaccuracies in the manufacture of the several parts, should they not be in absolute axial alignment and slightly out of line. It should also be noted that the mounting of the closure plate bearing on the trunnion sleeves 42' and 43 is in the same manner as above described, so that the shaft 48 may be angularly adjusted to compensate for wear and slight inaccuracies in the alignment of the parts.

In the modifications above described, the pump cylinder ring was driven by the prime mover, which, through its connection by the double hinge vane, effected the rotation or drive of the pump rotor. It has been found that substantially the same results can be obtained by driving the shaft and holding the cylinder ring stationary and allowing the pump rotor to roll within the cylinder ring and this rolling effected by the eccentricity of the shaft.

This latter construction is illustrated in Figs. 15 to 18 inclusive, wherein use is made of the same motor drive as disclosed in Fig. 10, and for a description of which reference to the above 25 may be had. As shown in Fig. 15, the pump shaft 48'' is provided at its upper end, see Fig. 17, with clutch teeth 134 which intermesh with the clutch teeth 114 at the lower end of the motor shaft 104. The eccentric portion 49'' of the shaft 30 48'' is encircled by the pump rotor member 135 disposed within the pump cylinder sleeve 136. The pump housing sleeve 136 is connected with the rotor member by the double hinged vane 58 in the same manner as above described, but this 35 pump cylinder sleeve 136 is secured against rotation by screws or bolts 137 passing through the plate 133 into the upper end of the sleeve 136.

The sleeve 136 is encased in a casting or lower housing member 138, and which housing member 40 has formed at its lower end a supply port 139 communicating with a vertical bore or port 140 in the lower end of the shaft 48''. At the outer end of the port 139 is the oil ball check valve 129.

45 The upper end of the shaft 48'' is provided with a vertical port 141, which communicates with the port 115 formed centrally of the motor shaft 104. The pump shaft ports 140 and 141 are respectively in communication with the 50 chambers in the pump cavity by way of ports 142 and 143, respectively, through the shaft 48'' and adapted to be connected respectively with ports 144 and 145 formed through the pump rotor member 135. Instead of having check 55 valves in these ports, use is made of combination supply groove and cut off ports in the shaft itself, which communicate with the ports 142 and 143 in said shaft. As shown in Fig. 16, the port 143 has connected therewith the open end 60 of a groove 146 formed through a portion of the periphery of the eccentric portion 49'' of the shaft, and which groove terminates in a shoulder 147. The port 142 likewise has connected therewith the open end of a groove 148 terminating at its other end in a shoulder 149. From 65 this it will be seen that there is a blank space between the ends or shoulders of these grooves and their ports which cut off any flow through the pump rotor ports 144 and 145 during a portion of each rotation of the pump drive shaft.

70 By this construction, the compression in the pump pressure chamber 46' is built up to the pressure in the pressure receiving tank before any additional compressed gas is forced thereinto, 75 and a suction is created in the chamber 46''

equal to the suction in the supply tank before the said supply tank is connected therewith. By this construction, a return surge from the pressure and supply tanks is prevented and at the same time the extraneous check valves are eliminated.

In Figs. 19 to 23 inclusive, there is illustrated means for adjusting the throw of the pump rotor, which may be employed for compensating for slight inaccuracies in machining the parts in order to have the proper tangential line contact between the said pump rotor and its housing, and may also be employed for taking up wear between these parts. It will be understood that this adjusting mechanism is applicable to any type of pump wherein a vane is employed for effecting the pumping operation, but for convenience in illustration, use is made in the drawings of the pump mechanism shown in Fig. 10, and enlarged for clear illustration. Accordingly, the pump rotor sleeve 47 has its bore slightly enlarged to accommodate a sleeve 160 which is mounted about the eccentric portion 161 of the pump shaft 162. The pump shaft 162 has projecting from its ends the trunnion portions 163 and 164 which are formed around the axis of the pump drive shaft, of which the clutch 114 is the only thing shown in Fig. 19. This axis is indicated by the point 165 in Figs. 20, 21 and 22. The shaft eccentric 161 is generated about an axis offset with respect to the axis for the shaft as a whole, and is indicated in Figs. 20, 21 and 22 by the reference character 166. The interior or bore of the sleeve 160 is likewise generated about the axis 166 of the shaft eccentric, while the exterior or outer surface of said sleeve is generated about an axis offset with respect to both the shaft axis 165 and the shaft eccentric axis 166, and is indicated by a point by the reference character 167.

Extending through the lower end of the shaft 162 and the trunnion 164 is a bore receiving an oscillatable rod 168. The rod 168 has projecting from its upper end a headed screw or shifter 169 which passes through a slot 170 in the shaft eccentric 161 and is received in an aperture 171 formed in the sleeve. Secured to the lower end of the rod 168 is a wrench or lever 172 having at its free end an elongated arcuate aperture 173 through which passes a clamp screw or bolt 174. The rod 168 below the screw 169 is hollow to receive a tube 175 which forms the supply port for the pump and is connected with the head 126 and supply conduit 127, and at its upper end forms the valve seat for the check valve 76, all as disclosed in Fig. 10, and as above described.

The parts as illustrated in Figs. 19 and 20 show them in normal position; that is, in pump operating position and with the pump rotor 47 having tangential line contact with the pump housing sleeve 39. In order that proper communication may be had between the pump chambers and the discharge port 68 at the top of the shaft and with the supply port at the bottom of the shaft, the eccentric sleeve 160 is provided with exterior circumferential grooves 176 and 177, respectively communicating with one or more bores 178 and 179 formed through the sleeve and in turn communicating with the grooves in the shaft eccentric which communicate with a bore leading to the shaft supply and discharge ports. Should, for some reason, the tangential line contact between the pump rotor and pump housing be too great as with the parts as illustrated for example in Fig. 20, it is only necessary to release the clamp

bolt 174 and shift the lever 172 forwardly as seen in Fig. 19 or in a counter clockwise direction as seen in Fig. 23, for thereby rotating or oscillating the rod 168 and through its screw or shifter 169 to shift the eccentric sleeve 160 in a clockwise direction as seen in Figs. 20 and 21 and thereby break or relieve the pressure at the point of tangential line contact. As will be seen in Fig. 21, the parts are so illustrated that with the adjustment just described, a clearance, indicated by the reference character 180 in Fig. 21, may be obtained. Should now, with parts as illustrated in Figs. 19 and 20, the proper tangential line contact not be established and a clearance exist, it is only necessary to oppositely operate the lever 172 for shifting the eccentric sleeve 160 toward the position illustrated in Fig. 22, which shows, by a dot and dash line, a portion of the inner wall of the pump cylinder sleeve 39 as being taken or cut away by the pump rotor member 47. In either position of adjustment, the lever 172 is then secured in position by the clamp screw or bolt 174. It will be appreciated that the shaft 162 is held against lateral or rotative movement by the lever 172.

From the foregoing, it will be noted that the throw of the pump rotor may be adjusted to vary the pressure at the tangential line contact and to take up wear on these parts without interfering in any wise with the operation of the pump.

In some instances, it may be desirable to automatically adjust the position of the rotor, as for example to relieve the pump of any contact of the rotor and its housing when starting the pump and subsequently to effect this contact. In order to do this, a mechanism is illustrated in Figs. 24 and 25. As there shown, the clamping screw 174 is dispensed with and the lever 172 has secured to it the inner ends 182 and 183 respectively of springs 184 and 185. The other end of the spring 184 is secured to a permanent anchor 186, while the other end of the spring 185 is connected with the movable core 187 of a solenoid 188. The spring 184 is utilized to shift the eccentric sleeve 160 and thereby the pump rotor 47 to the position illustrated in Fig. 21, while the solenoid is employed to shift these parts from this position to the desired pumping contact position which may be anywhere between the position shown in Fig. 21 and that shown in Fig. 22 and passing through the position shown in Fig. 20. The spring 185 being employed to cushion the contact and to form a yielding connection and avoid excessive pressure at the line or point of tangential line contact, due to the pull of the solenoid.

In Fig. 25, there is diagrammatically illustrated an electric motor armature 189 having associated therewith the starting and running field coils 190 and 191. The starting coils 190 have their opposite ends connected with the power lines 192 and 193, with a cut-out switch 194 connected therein and which switch is normally yieldingly closed as illustrated. The running coils 191 have their opposite ends likewise connected with the power lines 192 and 193, having imposed in the circuit the coil of the switch opening solenoid 195. The closing of the running coils circuit and likewise energization of the switch solenoid 195 completes a circuit through said switch, which includes the solenoid 188 for adjusting the position of the pump rotor.

The operation of this mechanism is as follows:

When the pump is stationary, the spring 184

actuates the lever 172 to a position for relieving all pressure between the pump rotor and its cylinder, such as illustrated in Fig. 21, so that there is substantially no load on the motor when the current is connected with the field starting coils 190. After the motor is running, the running coils 191 are automatically connected in and simultaneously and automatically energize the solenoid 188 for attracting the core 187 and thereby shifting the pump rotor into contact with the housing.

With this construction, a motor may be employed having a relatively low starting torque, which, when in operation, does the same amount of work and just as efficiently as the high starting torque motor as heretofore employed.

From the foregoing, it will be seen that there has been provided a pump or compressor mechanism in which the friction has been reduced to a minimum, since the only moving parts of the pump slide or oscillate on one another for a short distance, which is the difference in the diameters of these parts, instead of having continuous sliding and rotating surfaces throughout the peripheries, as is the case with the usual type of pump constructions. It will further be noted that this result is obtained whether the pump cylinder or the normal pump rotor member is the driven member of the unit. By this construction also, the parts may be so arranged and assembled as to take up the smallest amount of space. It will further be appreciated that with the construction above the throw of the pump rotor is fully adjustable to take care of possible small errors in machining and to take up possible wear between the pump housing and pump rotor.

What is claimed is:

1. In a pump mechanism of the class described the combination of a pair of housing members adapted to be connected with each other for completely inclosing the pump mechanism and each having a bearing in alignment with each other, a pump cylinder member having at its opposite ends journals, journaled in the housing members' bearings, a pump rotor member within said cylinder member, a shaft having its ends journaled in the pump cylinder member journals and having intermediate its ends an eccentric portion, said eccentric portion forming a journal for and being encircled by the rotor member and the eccentricity of said portion being such as to cause the rotor member to bear against and have line contact with the inner peripheral wall of the pump cylinder member, a pump wing simultaneously hingedly connecting with the pump cylinder member and rotor, and means for driving one of said pump members.

2. In a pump mechanism of the class described the combination of a pair of housing members adapted to be connected with each other for completely inclosing the pump mechanism and each having a bearing in alignment with each other, a pump cylinder member having at its opposite ends journals, journaled in the housing members' bearings, a pump rotor member within said cylinder member, a shaft having its ends journaled in the pump cylinder member journals and having intermediate its ends an eccentric portion, said eccentric portion forming a journal for and being encircled by the rotor member and the eccentricity of said portion being such as to cause the rotor member to bear against and have line contact with the inner peripheral wall of the pump cylinder member thereby forming around the rotor a pump cham-

ber, a double hinge pump wing between said pump cylinder member and rotor member dividing the pump chamber into a suction chamber and a compression chamber, a prime mover for effecting relative movement between the pump cylinder member and rotor member, and conduits respectively connected with the pump suction and compression chambers for respectively supplying a medium to be compressed and carrying off the compressed medium.

3. In a pump mechanism of the class described the combination of a pair of housing members adapted to be connected with each other for completely inclosing the pump mechanism and each having a bearing in alignment with each other, a pump cylinder member having at its opposite ends journals, journaled in the housing members' bearings, a pump rotor member within said cylinder member, a shaft having its ends journaled in the pump cylinder member journals and having intermediate its ends an eccentric portion, said eccentric portion forming a journal for and being encircled by the rotor member and the eccentricity of said portion being such as to cause the rotor member to bear against and have line contact with the inner peripheral wall of the pump cylinder member thereby forming around the rotor a pump chamber, a double hinge pump wing between said pump cylinder member and rotor member dividing the pump chamber into a suction chamber and a compression chamber, a prime mover for effecting relative movement between the pump cylinder member and rotor member, conduits respectively connected with the pump suction and compression chambers for respectively supplying a medium to be compressed and carrying off the compressed medium.

4. In a mechanism of the class described the combination of a pair of housing support members adapted to be connected to each other to form an hermetically sealed housing, said housing members each having a bearing boss in axial alignment with each other and respectively bored to provide bearings, a motor field carried by one of the housing members interiorly thereof, a motor armature centrally of the field, a pump cylinder sleeve, end plates carried by the pump cylinder sleeve and respectively provided with bored journals, journaled in the housing bearing bosses, said pump cylinder sleeve and end plates forming the means on which is mounted the motor armature laminations, a shaft centrally of the pump cylinder sleeve and journaled in the bores of the end plates' journals, an eccentric on the shaft within the pump cylinder sleeve between the end plates, a pump rotor journaled on the eccentric whose eccentricity is such as to cause the pump rotor member to bear against and have line contact with the inner peripheral wall of the cylinder sleeve to form around the rotor a pump chamber, a pump vane between the pump cylinder sleeve and pump rotor adapted to drive the rotor by the sleeve around the shaft eccentric and said vane being adapted to divide the pump chamber into a suction chamber and a compression chamber, and means providing a source of supply of a medium to be compressed to the suction chamber and storage for the compressed medium from the compression chamber.

5. In a mechanism of the class described the

combination of a pair of housing support members adapted to be connected to each other to form an hermetically sealed housing, said housing members each having a bearing boss in axial alignment with each other and respectively bored to provide bearings, a motor field carried by one of the housing members interiorly thereof, a motor armature centrally of the field, a pump cylinder sleeve, end plates carried by the pump cylinder sleeve and respectively provided with bored journals, journaled in the housing bearing bosses, said pump cylinder sleeve and end plates forming the means on which is mounted the motor armature laminations, a shaft centrally of the pump cylinder sleeve and journaled in the bores of the end plates' journals, an eccentric on the shaft within the pump cylinder sleeve between the end plates, a pump rotor journaled on the eccentric whose eccentricity is such as to cause the pump rotor member to bear against and have line contact with the inner peripheral wall of the cylinder sleeve to form around the rotor a pump chamber, a pump vane between the pump cylinder sleeve and pump rotor adapted to drive the rotor by the sleeve around the shaft eccentric and said vane being adapted to divide the pump chamber into a suction chamber and a compression chamber, means providing a source of supply of a medium to be compressed to the suction chamber and storage for the compressed medium from the compression chamber, said shaft being centrally bored from opposite ends to provide a supply port and a discharge port respectively for the supply and compression chambers, and one way check valves between the last mentioned ports and the source of supply and storage.

6. In a mechanism of the class described the combination of a pair of housing support members adapted to be connected to each other to form an hermetically sealed housing, said housing members each having a bearing boss in axial alignment with each other and respectively bored to provide bearings, a motor field carried by one of the housing members interiorly thereof, a motor armature centrally of the field, a pump cylinder sleeve, end plates carried by the pump cylinder sleeve and respectively provided with bored journals, journaled in the housing bearing bosses, said pump cylinder sleeve and end plates forming the means on which is mounted the motor armature laminations, a shaft centrally of the pump cylinder sleeve and journaled in the bores of the end plates' journals, an eccentric on the shaft within the pump cylinder sleeve between the end plates, a pump rotor journaled on the eccentric whose eccentricity is such as to cause the pump rotor member to bear against and have line contact with the inner peripheral wall of the cylinder sleeve to form around the rotor a pump chamber, a pump vane between the pump cylinder sleeve and pump rotor adapted to drive the rotor by the sleeve around the shaft eccentric and said vane being adapted to divide the pump chamber into a suction chamber and a compression chamber, means providing a source of supply of a medium to be compressed to the suction chamber and storage for the compressed medium from the compression chamber, lubricant storage means within the inclosing housing, and means for supply said lubricant to the medium as it passes between the supply source and pump suction chamber.

7. In a mechanism of the class described the combination of a pair of housing support members adapted to be connected to each other to form an hermetically sealed housing, said housing members each having a bearing boss in axial alignment with each other and respectively bored to provide bearings, a motor field carried by one of the housing members interiorly thereof, a motor armature centrally of the field, a pump cylinder sleeve, end plates carried by the pump cylinder sleeve and respectively provided with bored journals, journaled in the housing bearing bosses, said pump cylinder sleeve and end plates forming the means on which is mounted the motor armature laminations, a shaft centrally of the pump cylinder sleeve and journaled in the bores of the end plates' journals, an eccentric on the shaft within the pump cylinder sleeve between the end plates, a pump rotor journaled on the eccentric whose eccentricity is such as to cause the pump rotor member to bear against and have line contact with the inner peripheral wall of the cylinder sleeve to form around the rotor a pump chamber, a pump vane between the pump cylinder sleeve and pump rotor adapted to drive the rotor by the sleeve around the shaft eccentric and said vane being adapted to divide the pump chamber into a suction chamber and a compression chamber, means providing a source of supply of a medium to be compressed to the suction chamber and storage for the compressed medium from the compression chamber, lubricant storage means within the inclosing housing, means for supplying said lubricant to the medium as it passes between the supply source and pump suction chamber, and means for separating the lubricant from the compressed medium on discharge thereof from the compression chamber to storage.
8. In a pump mechanism of the class described the combination of a pump cylinder sleeve member, a pump rotor member, a shaft mounted concentrically with respect to the pump cylinder sleeve member and having an eccentric portion within the pump cylinder sleeve on which is journaled the pump rotor and the eccentricity being such as to eccentrically arrange the pump rotor with respect to the pump cylinder sleeve so as to have tangential line contact between the pump cylinder sleeve member and rotor member, said pump members being so mounted for rotation as to have one of them driven around the axis of the shaft, an electric motor connected with said one driven member to effect its drive and rotation, means for changing the eccentric throw of the shaft and thereby changing the eccentric arrangement of the pump cylinder sleeve member and pump rotor member including a sleeve journaled on the shaft eccentric, said shaft eccentric sleeve having an outer surface developed about an axis eccentric to the axes of the shaft and its eccentric, an arm for revolving the shaft eccentric sleeve around the shaft eccentric to add or subtract its eccentricity to that of the shaft eccentric and thereby change the throw of the shaft eccentric, spring means for actuating the arm to subtract the sleeve eccentricity from the shaft eccentricity, and electro-magnetic means operable with the pump member driving electric motor for adding the sleeve eccentricity to the shaft eccentricity.

JESSE S. WENTWORTH.
